CLAIM

The ornamental design for combined pencil sharpener and holder for writing instruments, as shown and described.

DESCRIPTION

FIG. 1 is a top plan view of a combined pencil sharpener and holder for writing instruments showing my new design;

FIG. 2 is a front elevational view;

FIG. 3 is a side elevational view, the opposite side being a mirror image thereof;

FIG. 4 is a rear elevational view;

FIG. 5 is a bottom plan view; and

FIG. 6 is a perspective view taken from the top.

FIG. 1.

FIG. 2.

FIG. 3.

FIG. 4

FIG. 5.
